W. J. BISHOP,
COIN CONTROLLED DOOR,
APPLICATION FILED JULY 9, 1919.

Patented Aug. 31, 1920.

2 SHEETS—SHEET 2.

UNITED STATES PATENT OFFICE.

WILLIAM JAMES BISHOP, OF COLLINGWOOD, ONTARIO, CANADA, ASSIGNOR OF ONE-HALF TO JOHN J. QUILTY, OF COLLINGWOOD, CANADA.

COIN-CONTROLLED DOOR.

1,351,609.

Specification of Letters Patent. Patented Aug. 31, 1920.

Application filed July 9, 1919. Serial No. 309,652.

To all whom it may concern:

Be it known that I, WILLIAM J. BISHOP, a citizen of Canada, residing at Collingwood, in the Province of Ontario, and Dominion of Canada, have invented certain new and useful Improvements in Coin-Controlled Doors; and I do hereby declare the following to be a full, clear, and exact description of the invention, such as will enable others skilled in the art to which it appertains to make and use the same.

This invention relates to new and useful improvements in coin controlled locks especially adapted for use on doors of the rotary type employed at theater entrances and other amusement places, and has for one of its objects the provision of means which requires the depositing of a coin before the lock can be actuated to admit a person.

Another object of this invention is the provision of means which will be entirely operated or controlled by the person entering the theater or other amusement place, thus obviating persons engaged for selling and collecting tickets at entrances, and which will admit only one person at each deposit of a coin.

A further object of this invention is the provision of a coin controlled door of the above stated character, which shall be simple, durable and efficient, and which may be manufactured and sold at a comparatively low cost.

With these and other objects in view as will become more apparent as the description proceeds the invention consists in certain novel features of construction, combination, and arrangement of parts as will be hereinafter more fully described and claimed.

For a complete understanding of my invention, reference is to be had to the following description and accompanying drawings, in which:

Figure 1 is a top plan view partly in section of a coin controlled door constructed in accordance with my invention.

Fig. 2 is a fragmentary longitudinal sectional view of the same drawn on an enlarged scale,

Fig. 3 is a vertical sectional view of the lock,

Fig. 4 is a detail sectional view illustrating the means for preventing the door from rotating in a reverse direction,

Fig. 5 is a plan view of an actuating arm,

Fig. 6 is a plan view of the locking and releasing elements,

Fig. 7 is a detail sectional view illustrating the means of supporting a coin in front of the plunger.

Referring in detail to the drawing, the numeral 1 indicates the entrance-way to a theater or other amusement place, and which entrance-way is closed by a rotating door 2. The upper end of the door is rotatably connected to the ceiling as illustrated at 3 while its lower end is provided with a semi-circular bearing 4 received within a cup or socketed member 5 embedded within the flooring 6. The door 2 consists of a central portion provided with radially extending panels 7 that are spaced apart and of such a distance that will only permit one person to stand between a pair of the panels. The length of the panels are such that they will come in close proximity to the walls of the entrance-way when moved adjacent thereto thus forming a complete closure to the entrance-way.

The flooring 6 is provided with a circularly arranged rack bar 9 which has its teeth directed in one direction adapted to be engaged by a dog 10 carried by the door 2 so that the door will be prevented or held from a reverse rotation.

A lock casing or housing 10' is embedded or located within the wall A adjacent the entrance-way 1 and is provided with a front wall 11 provided with spaced openings adapted to receive the arms 12 and 13 of a substantially U-shaped member 14 which has its bight portion pivoted to the casing as illustrated at 15. The arm 12 is adapted to form a latch bolt and normally protrudes beyond the front wall 11 of the casing or housing 10' and within the path of the panels 7 of the rotating door to prevent said door from being turned or rotated or admitting persons to the theater or other amusement place.

The other arm 13 forms an operating member that has its end beveled as shown at 16 and normally confined within its respective opening. A coil spring 17 is connected to the bight portion adjacent the arm 12 of the substantially U-shaped member 14 and to the casing or housing 10' for the purpose of automatically retracting the arm 12

when released. The arm 12 is held in an extended position by a spring pressed dog 18 pivoted within the casing or housing. An actuating member or arm 19 is pivoted 5 in the casing and has one end disposed against the beveled face of the dog 18 while its opposite end is disposed in alignment with the spring actuated push button 20. The spring pressed push button 20 is slidably 10 mounted within the front wall 11 and also in a bracket 21 located within the housing or casing. The last named end of the actuating arm or member 19 is provided with an opening 22 of a size sufficient to freely receive the push button when the same is 15 pushed inwardly so as not to affect or rock the actuating arm or member 19 on its pivot. A coin chute 23 opens outwardly through the front wall and has its lower end terminating at a point adjacent the inner end of the push button and the opposite end of the actuating arm or member 19 so that a coin will be conveyed to this point. A coin box 24 is located within the casing or housing 20 25 directly under the lower or inner end of the coin chute 23 and has mounted thereon a leaf spring 25 which is disposed under and adjacent the inner end of the push button for the purpose of supporting the coin as it 30 leaves the inner end of the chute 23. The coin supported by the leaf spring 25 will close the opening 22 in the actuating member or arm 19 so that on a person pushing the push button inwardly the arm or member 35 19 will be rocked on its pivot disengaging the dog 18 from the substantially U-shaped member 14 which is rocked upon its pivot under the influence of the spring 17 retracting the locking arm 12 and extending 40 the arm 13. When the locking arm 12 is retracted, the panel of the door previously engaged by the same moves in the direction of the arm 13 and engages the beveled end of the same, again rocking the substantially 45 U-shaped member 14 on its pivot returning the locking arm 12 to its initial position to be engaged by the adjacent panel of the door; thus it will be seen that the person barred by the first named panel is admitted 50 to the theater or other amusement place. As soon as the substantially U-shaped member returns to its initial position, the spring moves the dog 18 downwardly and locks the locking bolt 12 in an extended position. 55 After the push button has been once pushed inwardly and the device actuated to free the

door, the coin has been moved beyond the end of the leaf spring 25 and on releasing the push button the coin drops into the coin box 24, thus it will be seen that the device 60 is entirely automatic in its resetting operation.

While I have shown and described the preferred embodiment of my invention, it will be understood that minor changes in construction, combination, and arrangement of parts may be made without departing from the spirit and scope of the invention as claimed.

Having thus described my invention, what I claim is:—

1. A device of the character set forth including a rotating door, a lock casing, a substantially U-shaped member pivoted within said casing and having one arm engaging the door to lock the same against rotation and its other arm held in a retracted position, tension means connected to the substantially U-shaped member, a locking means engaging the substantially U-shaped member, a push button in said casing, and a coin chute in said casing conveying a coin to a point for permitting the push button to actuate the locking means.

2. A device of the character set forth including a rotating door, a lock casing, a locking member slidably mounted in said casing and engaging the door, a spring pressed locking dog holding the locking member in an extended position, tension means connected to the locking member, an arm pivoted in said casing and having one end in engagement with the dog and its other end apertured, a push button in said casing and adapted to move through the opening in the arm, a coin chute terminating adjacent the apertured end of the arm and inner end of the push button, a coin box in said casing under the end of the coin chute, a leaf spring carried by said box for supporting the coin in front of the opening in the arm and a member formed on the locking member and having a beveled end to be engaged by the door during its rotation for returning the locking member to its extended position.

In testimony whereof I affix my signature in presence of two witnesses.

WILLIAM JAMES BISHOP.
